UNITED STATES PATENT OFFICE.

FRANK K. WAY AND FRANK M. WATERS, OF DAYTON, OHIO, ASSIGNEES TO
THE PASTEUR-CHAMBERLAND FILTER COMPANY, OF SAME PLACE.

AIR-VALVE.

SPECIFICATION forming part of Letters Patent No. 507,770, dated October 31, 1893.

Application filed April 9, 1891. Serial No. 388,221. (No model.)

To all whom it may concern:

Be it known that we, FRANK K. WAY and FRANK M. WATERS, citizens of the United States, residing at Dayton, in the county of 5 Montgomery and State of Ohio, have invented certain new and useful Improvements in Air-Valves, of which the following is a specification.

Our invention relates to improvements in 10 air-valves adapted to permit the escape of air or gases from closed vessels, and at the same time prevent the escape of liquids therefrom.

The invention is especially adapted for use 15 with filters operating under the system known as the "Système Pasteur," though its usefulness is not limited to this particular class of mechanism.

The object of our invention is to provide 20 an air-valve which shall be more certain in its operation, which shall be free from the liability of sticking and at the same time will operate under pressure without discharging any liquid at the moment or in the act of closing.

25 Our invention consists in the constructions and combinations of parts hereinafter described and set forth in the claims.

In the accompanying drawings, Figure 1 is 30 a sectional elevation view of a device embodying our invention. Fig. 2 is a bottom plan view of the same. Fig. 3 is a detailed view in perspective of the outer casing. Fig. 4 is a sectional elevation showing a modification.

Like parts are indicated by similar letters 35 of reference throughout the several views.

In the said drawings, A represents an outer 40 casing in which is located a float A', slightly smaller than said casing and preferably formed of hollow thin sheet metal, hermetically sealed. The outer casing A, is provided at the bottom with an opening a, which communicates with a valve-chamber B, arranged below said casing; the valve-chamber B, and the outer casing A, being preferably formed 45 in separate pieces, screw-threaded and joined together with a suitable intervening packing-ring a', as shown. Projecting through the opening a, into the valve chamber B, is a valve stem b, securely connected to the float 50 A'. This valve stem b, is preferably tapered

from the top downwardly; being smaller where it joins the float A', the base or largest diameter of the stem b, being preferably of a size adapted to fit snugly, though not tightly, in the opening a. Attached to the valve-stem 55 b, is a valve b', which consists preferably of a washer of any suitable material, such as rubber, leather or indurated fiber, which valve is held in position by a metal washer b², and a screw b³, the screw passing through the respective washers b' and b², and into the valve stem b.

The lower portion of the outer casing of the valve chamber B, is preferably screw-threaded or otherwise adapted to be connected to the 65 vessel to which it is to be applied; a passage c, being adapted to establish a communication between said vessel and the valve chamber B.

It will be understood that the valve chamber 70 B and the valves therein are located below the float and the float chamber. The outer casing A, of the float chamber is left open at the top, and the float is formed with a projecting portion A², which extends through 75 the top of said casing A.

In the operation of the device the air or other 80 gases escaping from the vessel, pass through the passage c, and the valve chamber B, into the casing or float chamber A, and thence around said float, escaping at the top of said chamber. If the vessel should become filled with liquid, it rises through the passage c, and valve chamber B, into said casing, thus raising 85 said float and closing the valve. As the float is raised the conical or tapered valve-stem b, gradually closes the opening a, in the bottom of the float chamber, thus gradually cutting off the supply of liquid, and at the same time guiding the valve b', to its seat 90 aboutsaid opening. The valve is thus slowly closed until the pressure of water or other liquid is sufficient to hold the valve firmly against its seat, when the further escape of the liquid into the float chamber is prevented. 95 By the arrangement of the float, as thus described, above the valve and valve chamber, the valve is completely surrounded with the water or other liquid before it begins to close and before the liquid has come in contact with 100

the float. Before the valve begins to close the water or other liquid has arisen into the float chamber and thus filled the valve chamber, and the opening *a*, connecting the two chambers, so that the valve closes slowly and naturally as the water rises against the float and any spurt of the water or other liquid through the top of the valve chamber or escape orifice by the sudden closing of the valve is prevented.

We preferably form the extended portion *A*², of the float *A*', with an outwardly and downwardly extended flange *A*³, adapted to extend over and cover the top of the casing *A*; the casing *A*, being preferably provided with small upwardly extending lugs or projections *d*, on which this flange or cap *A*³, is adapted to rest. The flange *A*³, thus forms a cap or shield for the top of the float chamber to prevent dust or other foreign substances from finding their way into the float chamber.

In Fig. 4, the casing *A*, is shown extended up about the float *A*'; the casing in this construction being preferably formed in two parts *A*¹ and *A*², screw-threaded together as shown, the extended portion *A*², being adapted to project through an opening *A*⁵, in the top of said casing, which forms the discharge opening of said casing.

By having the top of the float extended through the opening in the top of the float chamber, means are at hand by which the valve may be readily depressed and thus separated from its seat in case any sticking of the same should occur; it being necessary only to press on the extended portion *A*², of the float, to loosen the valve.

It is obvious that other modifications than those described of the constructions herein may be employed without departing from the spirit of our invention. We do not therefore limit ourselves to these constructions, but

We claim, broadly—

1. An air valve, substantially as described, consisting essentially of a valve chamber and a valve therein, a float chamber communicating with said valve chamber and a float connected to said valve, said float being arranged above said valve and provided with an extended portion adapted to project through the

open top of said float chamber, substantially as specified.

2. In an air valve a valve and a valve chamber, a float above said valve, a valve seat between said float and valve, and a tapered or conical stem connecting said valve and float through said seat, said tapered or conical stem being arranged with the enlarged portion or base next to said valve, substantially as specified.

3. In an air valve a float arranged in a float chamber and connected with a valve below said float chamber, said float being extended above said float chamber and provided with a flange to form a cap or cover for said float chamber, substantially as specified.

4. A valve, a valve chamber, a float arranged in a float chamber above said valve, said float being provided with an outer flange to form an outer cap or cover for said float chamber, and engaging projections between the top of said chamber and cap to prevent the tight closing of said chamber, substantially as specified.

5. A valve chamber and a float chamber, a perforated valve seat between the same, a tapered valve stem connecting said valve and a float through said seat, said float being arranged above said valve and provided with an extended portion which projects through the top of said float chamber, substantially as specified.

6. In an air valve a valve chamber, and a float chamber above said valve chamber, a perforated valve seat at the top of said valve chamber, and a float in said float chamber connected through said valve seat to said valve, and a cap or cover for said float chamber, and engaging projections between the top of said float chamber and said cap or cover, to form an air passage under said cap or cover, substantially as specified.

In testimony whereof we have hereunto set our hands this 31st day of March, A. D. 1891.

FRANK K. WAY.

FRANK M. WATERS.
